UNITED STATES PATENT OFFICE

ABRAM FRANK PAUL, OF LLANERCH, PENNSYLVANIA, ASSIGNOR TO NATIONAL PNEUMATIC COMPANY, OF NEW YORK, N. Y., A CORPORATION OF WEST VIRGINIA

REMOTELY-CONTROLLED TRAPDOOR AND STEP FOR CARS

Application filed November 8, 1929. Serial No. 405,796.

This invention relates to what is commonly known as trap doors for covering and protecting the steps of passenger railway coaches or carriages. The trap is necessary to take care of the high and low level platforms that are encountered at various stations and serves to cover the car steps and thereby protect passengers from falling out.

In the present form of railway coaches the trap doors are raised or lowered by hand by members of the train crew. Since there is usually a greater number of coaches than members of the train crew it is necessary that the traps and doors be opened some time before the train stops and then again closed after the train has started, thereby endangering passengers while the steps are unprotected. By my invention the above named and other disadvantages are overcome.

Moreover a single guard or attendant may operate all the traps and doors on the train when the train stops.

The object of my invention therefore is to provide a trap and step construction which will safeguard passengers and which will permit of remote control either on the train or from the station platform.

Another object includes the provision of means for moving the treads of the car steps into trap door formation, so as to close the stair well or trap, and then utilize the same means for opening the trap and moving said treads again into stair forming position so as to form the vestibule stairs on railway cars or the like.

A further object includes the provision of means for effecting the above purposes of my invention, which means are comparatively simple and may be readily applied to a standard railway coach.

In order to accomplish these purposes I provide step moving mechanism for moving stair treads from stair formation into trapdoor formation and then back again into stair formation to either close the stair well of passenger coaches or to form the car steps. These purposes may be accomplished by various forms of construction whereby the steps are moved and held in position. In one form I utilize movable plates for raising and

lowering the steps. Another way of carrying out the above purposes includes the provision of carriage means for bodily moving and lowering the steps. These carriage means may be operated by a system of levers as will be more fully set forth, or the carriages may be moved up and down by a system of vertical worms and gears to operate said worms.

Other objects will appear hereinafter and I attain these objects by the construction shown in the accompanying drawings in which—

Figure 1 is an end view of a portion of a car vestibule showing the steps made and operated in accordance with the principles of my invention;

Fig. 2 is a view showing the movable plate in its uppermost position with the steps in trap door formation;

Fig. 3 is a plan view of a portion of a car vestibule equipped with my stairs and trap;

Fig. 4 is a view looking in on the car steps from a low level station platform;

Fig. 5 is a view taken on the line 5—5 of Fig. 6, showing a form of stairs wherein the steps are moved by carriages which are operated by levers;

Fig. 6 is a rear view of the stairs and operating mechanism shown in Fig. 5;

Fig. 7 is a diagrammatic outlay showing one form of remote control mechanism suitable for operating the motors which operate the stair control mechanism.

Like reference characters refer to similar parts throughout the several views.

In a preferred form of mechanism the treads of car stairs, for example, are moved into and out of position by a series of slotted plates on each side of the steps. These plates are provided with slots in which slide the guiding members or pins on the ends of the stair treads. In the form of construction shown in Figs. 1, 2, 3 and 4 the two outer plates 20 and 21 are fastened to the car frame while the two inner plates 22 and 23 are movable up and down and are operated by suitable mechanism. The outer fixed plates are provided with the parallel slots of suitable length so as to support each tread in its stair

forming position. The movable plates are provided with coregistering slots which serve to pick up the steps and move them into trap door formation, as will be set forth 5 more fully below.

Where the carriage mechanism is used for moving the treads of the steps into and out of stair forming position, in one form, I provide rollers on the carriages which fit in 10 angle iron posts at the four corners of the stair well for guiding the carriages as they move up and down. In this form of construction the carriages are preferably operated by levers which are mounted pivotally and operated by a suitable motor.

Any suitable operating means may be used for operating the step moving mechanism, such as mechanical, pneumatic or electric motors which are known to the art.

Referring now to the drawings, the two stationary or fixed plates 20 and 21 are fastened to the car frame 24, and are held by means of rivets 36 or the like. These plates are spaced apart and form the sides of the 25 stair well. The said fixed plates are provided also with vertical slots which are shown in dotted lines on Fig. 1. In the construction shown these slots are grouped in pairs of different lengths and coincide with the 30 fixed position of the stair steps. That is to say, each fixed plate is provided with pairs of slots 16, 17, 18 and 19 reaching from near the top of the plate to the step forming position of the treads and by which the treads are 35 supported and guided.

On the inside of said fixed plates movable plates 22 and 23 are provided. These plates are also provided with pairs of slots 40, 41 and 42 of lengths which vary with the position of the treads as is best shown in Fig. 2. The steps are made up of movable stair treads 30, 31, 32 and 33. These treads have two projections, or pins 34 at each end which rest in the bottom of the slots of the fixed 45 plates and serve as supports for the treads. Said projections also extend through the slots in the movable plates and serve as means for raising and lowering the treads. It will be noted that there are no slots for the tread 50 or step 30 in the movable plates and that said tread therefor moves the same distance with the plates. On the other hand step 31 remains at rest in slots 17 of the fixed plates while the movable plates move the length of 55 slots 40, which is equal to the height of tread-riser 35, before step 31 is picked up and moved to trap door formation. Likewise, slots 41 and 42 are of suitable lengths to take care of treads 32 and 33 respectively, for moving said treads into trap door formation.

When now it is desired to close the stair well the plates 22 and 23 are raised by suitable operating mechanism, by the toggle links 43 which in turn are moved by the two 60 rock shaft arms 44 on the rock shaft 45

through the rock shaft lever 46 and motor operated link 47 which is operated by a suitable motor 48 controlled through the magnet valve 49 in the usual and well known manner known to the art.

It will be understood that the trap door formed when the stairs are in trap door formation is flush with the vestibule floor 70 25 so that passengers can walk out on high level platforms when the train door 29 is 75 opened. This door is moved into and out of the door slide 29 in the usual and well known manner by means not herein shown. The end of the train vestibule is shown in the drawings at 26, the car side at 27, and the 80 roof at 28.

Where the stair moving mechanism includes the movable carriages of the type disclosed in Figs. 5 and 6, for example I provide at the corners of the stair well four angle irons 50. These angle irons are properly supported and serve as tracks for the end carriages 51 and 52. These carriages consist of horizontally placed angle irons 53 having rollers 54 and 55 suitably braced. On each 85 side of the steps there is a plate 56 and 57 provided with slots 58, 59, 60 and 61, in which slide the projections 62 on each side of the stair steps. Suitable brackets 63 on each plate provide supports for the treads 90 in stair step formation.

The carriages are moved up and down by the movements of the lever arms 64 pivoted on the rocker bar 65 and operate by a suitable motor 66. The rocker bar is held in 100 position by two straps 67. It will be noted that when the carriages 51 and 52 move up, that the several steps 30', 31', 32' and 33' will be picked up in succession and moved into trap door formation at the top of the 105 side plates 56 and 57, thereby closing the stair well to protect passengers while the car or train is moving and thus providing means for passengers to enter from or alight on, high level platforms.

The stair and trap door mechanism may be remotely controlled by appropriate means, one form of which is shown in Fig. 7. In the diagrammatic showing of Fig. 7 the car or coach 100 is provided with trap door 110 stair construction 101 of the remotely controlled type herein disclosed and claimed. Said stairs and trap doors are operated by suitable means as magnet valves 49 and motors 48 when the corresponding switches or 115 controls 90 (or the platform controls 91) at either end of the car are closed. The magnet valves and motors are of known construction and are not the subject of this invention. Current for operating said valves, or 120 for use on electric motors, as motor 76 for example, may be taken from any suitable source as a battery 102.

I claim:

1. In remotely controlled stairs and trap 125

doors the combination of stair treads and fixed plates having slots, pins on said treads to engage said slots, movable plates adjacent said fixed plates and operatively connected to the treads, and levers for moving said movable plates to move said treads into and out of trap formation.

2. In remotely controllable stairs and trap doors, the combination of a plurality of stair treads having projecting pins on their edges, two movable slotted plates within which the pins of the treads project, the slots in the plates for each tread being of progressively increasing length from the lowermost tread to the uppermost tread, and means for moving the plates to cause the treads to be progressively picked up and moved into and out of trap formation, said plates acting to move the treads to step formation whenever they bind.

In testimony whereof I have hereunto set my hand on this 10th day of May, A. D., 1929.

ABRAM FRANK PAUL.
